UNITED STATES PATENT OFFICE.

JEAN BILLITER, OF ASCHERSLEBEN, GERMANY.

PROCESS FOR THE ELECTROLYSIS OF LIQUIDS.

No. 903,951.

Specification of Letters Patent.

Patented Nov. 17, 1908.

Application filed August 3, 1908. Serial No. 446,720.

To all whom it may concern:

Be it known that I, JEAN BILLITER, subject of the Emperor of Austria-Hungary, residing at Aschersleben, in Germany, have 5 invented certain new and useful Improvements in Processes for the Electrolysis of Liquids, of which the following is a specification.

Many attempts have already been made to 10 utilize the alterations of specific gravity which occur during electrolysis in the stratification of the electrolyte, for the purpose of better separating the products at the anode and cathode from each other. Examples of 15 such processes, which especially relate to the electrolysis of chlorids, have been described *e. g.* in German Patents 141187 and 191234. On the other hand Le Sueur, Hargreaves and Bird, Carmichael and others 20 have sought to prevent the mixing of the anode and cathode solutions by supplying the cathode-chamber with electrolyte-solution from the anode, so that the solution fed in flows in the opposite direction to the 25 movement of the OH-ions. As is known, such arrangement of the flow is not sufficient to prevent the electric transfer of the OH-ions to the anode. A more effectual 30 method of combating this is to cause the solution containing the alkali to separate itself as a heavier layer from the anode solution above it and to control the supply of fresh solution in such a manner that the 35 concentration of chlorin ions in the layers next to the anode is at a maximum. This arrangement however is also insufficient alone.

A process, which seeks to combine the 40 advantages of the two methods of working above mentioned, has been described in German Patent 191234. As in the bell cell process (German Patent 141187), however, there is required in the said patent, a motion of the lower layer, in order to maintain the 45 stratification or to continuously reform the separating layer. The circulation of the solution must therefore take place at a relatively rapid rate as in the bell cell process. By this means, however, the concentration 50 of the lyes which can be obtained with good yields would again set an upper limit fairly soon. Moreover, cells of this kind are very sensitive to variations of pressure in the gas-chamber, such as frequently occur in technical work, since the oscillations of the liquid caused thereby involve destruction of

the stratification. With the same current, however, higher concentrations of the alkali can be obtained and the method of operation is made much more convenient and simple, 60 if the stratification is maintained without lateral motion of the layers of liquid, and if, using closed cells (without overflow) only the lowermost, densest layer, which contains most alkali, is employed for feeding the 65 cathode chamber. This object can be attained by making a cell with a horizontal arrangement that maintains a stratification by heating from above, which has the supply of feed solution at the level of the heating 70 pipes and in which the cathode-chamber is fed solely by the passage through the diaphragm of the heaviest layer which is richest in alkali, lying directly above the diaphragm and contained in the diaphragm. 75

Extended technical investigations on a large scale have shown that the stratification is produced more advantageously by heating the solution which is in the neighborhood of the upper electrode and which is 80 to separate itself as the upper layer, instead of allowing it to become weak. The heating is preferably affected by heating pipes, which in contradistinction to all known arrangements are arranged above the upper 85 electrode, when this is mounted horizontally, and at the level of this electrode when it is arranged vertically (for example in the form of vertical downwardly-extending rods), or by means of steam which is conducted into the space above the surface of the liquid. The advantage which is obtained by this means is considerable. Hot concentrated salt-solution can be electrolyzed at 90 the upper electrode, so that the resistance of the bath is lower and the current density (with the same pressure) is higher, and the life of the electrodes is increased since they are generally more rapidly destroyed in dilute solutions, in cases in which soluble 95 gases are given off at the upper electrode (for example in the electrolysis of the chlorids of alkalies) their solubility is decreased by the elevated temperature and the interaction between the dissolved gases and the 100 products of electrolysis in the lower heavy layer is reduced, and so on. By means of a cell constructed as hereinafter described from this point of view, it is possible to employ the heaviest layer containing the greatest amount of alkali alone for feeding the 105 cathode-chamber arranged beneath the dia- 110

phragm, this being effected solely by the supply through the diaphragm.

One constructional form of the improved cell is shown in the accompanying drawing.

5 For receiving the solution, a tank 2 of heavy iron plate lined with cement 1 is employed. The heating pipes 14 and the supply pipe 17 for the solution to be fed in are arranged at the level of the upper electrodes 9 for the purpose of maintaining the stratification and to enable the solution supplied to be brought directly to the maximum temperature in the tank by means of the heating pipes, in order that their chlorinating ions shall have the highest possible velocity of diffusion. The horizontally mounted diaphragm 4 lies directly on the wire net-work 3 forming the cathode. In order to provide room for the easy escape of the gases generated on this network, carriers 16 are employed which are mounted on the one hand on the iron bottom of the tank and which support the slightly corrugated wire network at several places, which would otherwise bend under the load of the contents of the bath. A double bottom is thus produced, through which the gases pass in order to be conducted away through a branch pipe or the like, while the lye runs away at the bottom. The carriers can be made of metal and can then simultaneously serve as terminals for the supply of the current.

The rapidity of the flow through the diaphragm can obviously be regulated by the 35 composition and thickness of the latter. If the thickness and composition of the diaphragm are already chosen, the rapidity of flow can be varied by adjusting the height of the liquid in the interior of the tank. 40 Since however the permeability of the diaphragms decreases somewhat in the course of time by the impurities which deposit themselves thereon, an arrangement can be adopted for the uniform feeding of the cathode-chamber, which permits a smaller or greater degree of vacuum to be produced in the lower space or chamber, in order to increase the flow of lye through the diaphragm. For this purpose, the run away 45 pipe 11 is provided with a branch 12, through which the gas can be drawn off. This branch pipe preferably extends upwards at an inclination in order that the current of gas shall not carry away any lye with it. Any 50 drops of liquid which may be carried along with the gas may be kept back by transversely mounted wire grids 18; by this means it is also possible to insure that any explosions of gas which may take place externally shall not extend into the interior of the bath. A slight vacuum can be produced in a very simple manner by causing 55 the branch pipe 12 to extend upwards, thus

producing the vacuum by the suction-effect of the rising hydrogen. The lye flows into 65 a collecting tank arranged beneath. The degree of vacuum can be seen from the position of the lye in the pipe 11. The chlorinating gas escapes from the anode compartment by a pipe 19 in the top of the tank 2.

70 By this method, simple, inexpensive and efficient cells can be made, in which in contradistinction to all earlier arrangements the cathode-chamber is fed solely by the layer of liquid which contains the greatest amount of 75 the products of electrolysis at the cathode. The said arrangement therefore gives the highest concentration of the lye with the best yield. The apparatus can obviously be also employed for the electrolysis of other than 80 chlorid solutions, and the lower electrode-chamber under special conditions may form the anode-chamber.

What I claim is:—

1. The process of electrolyzing liquids, 85 which comprises feeding the liquid to the upper one of electrode chambers at different levels and separated by a diaphragm and heating the liquid in the upper chamber.

2. The process of electrolyzing liquids, 90 which comprises feeding the liquid to the upper one of superposed electrode chambers separated by a diaphragm and heating the electrolyte at or above the electrodes in said chambers.

95 3. The process of electrolyzing liquids which comprises feeding the liquid on to a heated surface contained in the upper one of superposed, diaphragm separated, electrode chambers at or above the level of the 100 electrodes in said chamber.

4. The process of electrolyzing liquids which comprises feeding the liquid to the upper one of two, diaphragm separated, 105 electrode chambers at different levels, heating the liquid at an upper level in the upper chamber and maintaining a suction in the lower chamber beneath the diaphragm to control the movement through the diaphragm.

110 5. The process of electrolyzing liquids, which comprises feeding the liquid to a heated surface in the upper one of two superposed diaphragm separated, electrode chambers and controlling the withdrawing of the 115 gas generated from the lower chamber beneath the diaphragm at a greater rate than the rate of formation of said gas to maintain a suction beneath the diaphragm.

In testimony whereof I have hereunto set 120 my hand in presence of two subscribing witnesses.

JEAN BILLITER.
